CLAIM

The ornamental design for a bottle cap, as shown and described.

DESCRIPTION

FIG. 1 is a top perspective view of a bottle cap in the closed position showing my new design;

FIG. 2 is a top perspective view of the bottle cap in FIG. 1 in an open position;

FIG. 3 is a right side elevational view of the bottle cap of FIG. 1;

FIG. 4 is a top plan view thereof;

FIG. 5 is a front elevational view thereof; and

FIG. 6 is a rear elevational view thereof.
